Box 311

James Thompson Baltimore Maryland

Solers-Patent

The Solemnity referred to in these Letters Patent and making part of the same containing a Description in the words of the said James Thompson himself of his improvement in the mode of constructing timber Rail Roads.

To all to whom these presents shall come. Be it known that I James Thompson of the City and County of Baltimore and State of Maryland have invented a new and useful improvement in the mode of constructing timber Rail Roads, and that the following is a full and exact description of the construction as invented and invented by me. A proprie to make roads of one, two, three or four Rail, or more as may be desired, said rails to be buried in sockets cut down into timber laid transversely with them at a distance from each other more or less apart, said timber to rest upon iron plates, posts, stone blocks, cast iron chains, supports, &c. alternately, as the nature of the earth may require in as many rows as there are track rails, except in one variation which will be hereafter mentioned. When a road is made to consist of but one rail, for the carriage to run upon it should be considerably elevated above the ground to admit of the carriage being suspended on each side, and sufficiently below the top of the rail to bring the center of gravity of the load and carriage below the top of it. There should also be another line of rail, below the top rail fastened to the outside of the posts, the outside of the rails being flat and straight and so confined to the posts as to produce the same distance through horizontally from end to end the whole length of the road for side or guide wheels to run against which will keep the carriage in an upright position although it may be loaded out of balance. The posts of which track may be driven or sunk into the earth or set upon it having a sufficient number in the earth and to a proper depth to secure its upright position. The posts may be stepped upon transverse steps, especially where the line of elevation of the rail is considerably above the earth, but these posts must have bases on each side, ranging from near the ends of the transverse blocks up to the

Post 14 (1)

posts intersecting them at the same line of elevation but sufficiently below the rails not to interfere with the carriage way of other post more or less may be driven into the earth or rest upon said timber. When two rows of posts, stone blocks, cast iron chains, & cedars are used for a two rail or single track they are to be determined by the transverse timbers. Seamed to the posts stone blocks, especially as will be herein after mentioned will be found to have notches cut down into them sufficiently deep and wide to bed securely the road rails, into by help of flons keys & otherwise.

When three rails are laid upon three rows of posts &c. the middle rail should be so wide as to allow the wheels of the cars to pass each other without touching and stand into transverse timbers as before described centrally over the posts stone blocks &c. The said three rails may be so distant as to allow the usual width of Head tracks, including the vacant space between them with only the inconvenience of the extension of the length of the wheel nodes. Two rails may be laid upon the above transverse timbers the notches being cut equidistant from the middle row of posts three feet apart more or less. But if four rails be laid upon four rows of posts stone blocks, cast iron chains, & cedars, they should be laid centrally over them but in that case a part of the transverse timbers may not extend through both tracks, but every other or second row. said road rails should be surrounded by cast or wrought iron plates, for the wheels to run upon, but to avoid the expense of iron plates I propose in some cases on lateral roads especially to make rails with wide timber rails. The carriage wheel's commanding in width and lined with thin iron and may have a double row of spikes to support the felloes, by which means of which they will not sink into the road of the rails due to obstruct their passage. In some cases I desire to drive down a short log a post sufficiently below the surface to obtain a solid foundation and to prevent from decaying then to stop the top post reaching to the road rail upon that, for the reason that when the bottom of the top post has decayed where it comes in contact with the earth so as to require its removal it can rarely be done and the bottom one will remain to support a new one. By this procedure the the exact and necessary length of the upper post can be measured and adjusted before it is put into its place and with more economy of time &c. I propose

Chas. 100 154
A suitable iron chain or pedestal, consisting of any other shape, twelve to eighteen inches diameter, more or less, running forward in the centre about three inches from a side, with a thinner part going forward, about one inch wide, with this only varying from near the centre out to the side with two studs or studs, those further more or less in length and about the same in height, parallel to each other and equidistant from the centre, and also at proper distance apart to receive the road rails, through which studs and rail upon may be driven to confine them together, and upon this inside of the outside chain is to be cast directly against the inside rail, that is stud, two other studs, at right angles, with the first mentioned stud nearly converging from the rail that at which place they both join half an inch at their outer ends, which last mentioned studs are to receive dovetailed tenons of the transverse timbers, which timbers are to reach from one chain to the other transversely of the road, and to confine the chains in their proper place, and to prevent their being crowded by lateral pressure. They may also be riveted down upon the iron for further security. The middle chains, must have studs on both sides of the middle or Road Rail, studs to receive the ends of the transverse timbers of the two tracks, the base of which iron chains may not exceed one eighth of an inch in thickness, between the rivets, being convex and strengthened by the rivets at proper distances, and also by the studs which confine the rails, or the transverse timbers, may be laid down upon the cast iron chains between the two first mentioned studs, and then the track rails upon them in notches, as in other cases, and then the road rail studs may be left off the chain when used in this way. These chains or pedestals may be calculated perpendicular to any satisfactory height, by raising a column consisting of plates about half an inch thick, four inches wide more or less, and sloping each other at right angles through the centre where they join, being cast in this form, they would probably afford the most strength for the same weight of metal, with a pin in the centre upon the top to pass up through the transverse timbers and into the road rail, which pedestals in this form would enable us to pass light hollow iron rail and rockers, as in general I propose the road for permanent carriage when no plate is necessary. Drawing
not

ings of the last description. The stakes may all be left off, or the culverts may be of any other form. All the above mentioned changes are practicable. I prefer to use chiefly in sand ridges where stone cannot be well found in hot climates where wood posts or piles would be subject to rapid decay and where the elevation of the road and earth will permit. When using stone blocks to support the transverse timbers. Holes should be made into them to receive pins which confine the transverse timbers upon them. A block of stone may be placed at the ends of said timbers, or to, or into the earth to prevent any lateral movement of said timbers. The joinings of all the posts from one timber and to another rails where they come in contact with each other are to be secured by pins. Keys or other means in the following manner and form. The tops of the posts are to be made true horizontally a little concurring upwards in the centre and all inclined to a certain angle at top from an inch or more down: leaving the edge of the shoulder should then be cut in reducing the posts a little sloping downwards from the posts out to the water. a hole is to be made in the tops and centres of said posts to receive a pin of sufficient size to confine the transverse timbers and to not easily to them. The transverse timbers are to have holes bored through the centres of the notches made for the track rails, to bed in, of a size conformable to them in the tops of the posts. The under sides of which timber shall be cut out a little concave, and sufficiently distant from the hole in the centre to fit on the tops of the posts, by which means and shape no water can insinuate itself into the joinings or on to the tops of the posts. It perhaps to bore holes into the under sides of the track rails nearly but not quite through and after the transverse timbers are adjusted to the tops of the posts a pin is to be driven into the holes made in the transverse timbers and tops of the posts, from on to the bottom leaving a sufficient length above to fill the holes in the under sides of the track rails, which rails are to be driven down upon said pins and into the notches cut down into the transverse timbers for that purpose and keys may also be driven between the rails and the sides of the notches for further security. said pins not reaching up through the rails will prevent water from descending into the posts, &c. as the pins may fall if just

100

fixed with the sole of the mattock under the nail must have a wedge or wedge
iron into it if necessary and then the sole fastened to the crossbeams,
or transverse timbers by hedges or other means. What follows is my
mention of improvement in the construction of timber Rail Roads; is the
elevation above the ground of the road rails, and the timber transversely
to them throughout the whole length of the road, and their mode of
construction set forth in the specification. They requiring but a slight
support from the earth to keep them in an upright position by means of
the cross timbers being strongly confined to the road rails by posts, &c. combs
and with the firm foundation of the road posts effected by the accounts
of posts which are driven into the earth, small stones under the stone
blocks, or cast iron chairs either kind to be used alternately, when
the elevation of the road or the nature of the earth may require it. Also
the right of driving or setting separate posts or piles from those confined
to the cross timbers aforesaid to obtain a firm foundation and its immunity
from decay by their being sunk sufficiently below the surface for that pur-
pose. Also the right to set posts upon the ground and sink them alter-
nately, or to step them upon cross timbers, with braces, or upon stone blocks,
or cast iron chairs and to drive them deep alternately for the necessary
immunity against lateral pressure. Also the three rail track upon three
rows of posts, cast iron chairs and stone blocks alternately as may be requi-
red by the nature of the earth &c. Also the four rail track upon three rows
of posts &c. Also the right of confining the cross timbers alternately through
the tracks or not, to road timber as may be found best in the four rail track
with four rows of posts &c. Also the under rail fastening the rail tracks
with the manner of setting the posts, upon pile foundation below the sur-
face and upon cross rails with braces, stones or iron chairs alternately.
Also reducing the tops of the posts to one size and cutting the tops becoming
also the shaping of the undersides of the transverse timbers to conform
to the tops of the posts. Also the cast iron chairs or pedestal secured upon
small stones, or solid rammed or powdered earth for a substrata for
wood posts, or stone blocks whereby the road timber and road rails have
a support without touching the earth. Also the right of under timber

will be shown now. Also the right of stepping the road posts upon crop land
and they to rest upon logs lying upon the ground lengthwise of the road
separated by braces at different parts of it. Also the extension of posts to an
unnatural distance from each other by the application of braces &c also the
wedges in the pins as set forth. Also the two end track as set forth in
the specification.
